Inventor:
Matt CRYM

UNITED STATES PATENT OFFICE

MATT CRYM, OF WATTIS, UTAH

RAIL FASTENER

Application filed March 6, 1930. Serial No. 433,644.

The invention relates to improvements in metal cross ties to hold parallel, standard T rails, used in railroad, industrial and mine tracks; the objects of the improvement are:

- 5 (1) To hold the rails firmly to gauge.
- (2) To provide a bearing for the rails.
- (3) To provide a simple and easy method of fastening the cross tie to the rails and likewise an easy method to disconnect the
- 10 cross tie from the rails.

One form of the invention is illustrated in the accompanying drawings, in which Fig. 1 is a plan view of the base or supporting member of the cross tie, Fig. 2 is a side view of the member shown in Fig. 1. Fig. 3 is a plan view of the complete cross tie and Fig. 4 is a side view of the complete cross tie. Figure 5 is a side elevation of one of the braces in place on the rail metal plate shown enlarged 20 over the size of the other views.

The bearing member, 1, Fig. 1 is a channel shaped piece of metal, the length and weight, depending on the gauge of the track and size of rails. To this member, 1, are securely fastened by rivets or other suitable manner, 25 two metal plates, 2, the middle portion of which is depressed to fit the base of the rail. Two rectangular slots, 3, are cut in the top through 1 and 2. Part 4 is a movable clip or rail brace, fastened to 1 by means of the bolt, 8, washer 9 and nut 10, so that it can be rotated as shown by the dotted lines in Fig. 3.

Part 4 is shaped to fit snugly the ball, web and base of the rail. Part 5 is an immovable clip or rail brace fitting snugly the web and base of the rail and is fastened firmly to 1 and 2 by means of rivets or in any suitable manner. Part 6 is a movable clip or rail brace similar in shape to part 5. It is fastened to part 1 by means of a bolt, 8, extending through the slot, 3, and the washer, 9, and nut, 10. The bolt, 8, is fastened to parts 40 4 and 6 by means of a rivet, 11. Part 6 can

rotate about bolt 8 as a center, as shown in dotted lines in Fig. 3.

Part 7 is a clip or rail brace similar in shape to part 4, and fastened immovably to 1 and 2 by rivets or by any suitable method. 50 Part 12 is a piece of spring steel or other suitable material fitting over the top of parts 4 and 6 and fastened to them by the rivet, 11. The object of this part 12 is to hold parts 4 and 6 firmly in place after the cross tie has 55 been fastened to the tie. The spring member 12 has one end bent downwardly which end is adapted to fit into the slots 3 to normally hold the parts 4 and 6 in secured position against the rails, holding the rails in fixed relation to the ties. The part 12 is disengaged by placing a sharp pointed bar under the edge of the part 12 and springing the end out of the slot 3, freeing the spring 60 12 so that it may be rotated laterally with 65 the parts 4 and 6.

An enlarged view of this movable clip 4 is shown in Figure 5. When it is necessary to rotate 4 the spring, 12, is raised to disengage the end, 13, from the slot 3 after which 70 4 may be rotated ninety degrees and also moved horizontally. Likewise, part 6 may be rotated and moved horizontally in the same manner, and the cross tie removed from the rails. To fasten a crosstie to the rails 75 the process is reversed. The cross tie is placed under the rails, with parts 5 and 7 bearing against them. Parts 4 and 6 are rotated and brought to bear against the rails and springs, 12, are allowed to fall in slots, 80 3, which holds 4 and 6 in place until it is desirable to remove the cross tie.

I am aware that prior to my invention metal cross ties have been made with movable and unmovable clips or fastenings to secure 85 the cross tie to the rails.

I therefore do not claim such a combination broadly; but, I claim:

In a device of the class described the combination of a metal tie having slots adjacent 90

the rail positions thereof; rail braces secured to said tie adjacent said slots; rail braces carried over said slots having bolts passed therethrough securing said braces slidably and 5 rotatively on said ties; a spring, having the end turned downward adapted to fit into said slot, carried on said braces and secured thereto by a rivet, said spring adapted to be raised from said slot to allow said braces to be 10 moved away from the rail or to be inserted in said slot to hold the rail braces in fixed relation to said rail tie and rail.

MATT CRYM.
